2 Sheets-Sheet 2

Technical drawing of a mechanical assembly, labeled Fig. 3. The drawing shows a top view of a horizontal frame 10. A vertical rod 8 is attached to the top of frame 10. A curved lever 7 is connected to the bottom of rod 8. A spring 20 is attached to the top of lever 7 and to a fixed point on frame 10. A small part 9 is attached to the top of lever 7. A slot 22 is cut into frame 10, and a part 19 is positioned within this slot. A horizontal rod 23 is attached to frame 10. A spring 30 is attached to the top of rod 23 and to a fixed point on frame 10. A curved lever 24 is connected to the bottom of rod 23. A spring 29 is attached to the top of lever 24 and to a fixed point on frame 10. A slot 21 is cut into frame 10, and a part 28a is positioned within this slot. A horizontal rod 27 is attached to frame 10. A spring 31 is attached to the top of rod 27 and to a fixed point on frame 10. A curved lever 25 is connected to the bottom of rod 27. A slot 26 is cut into frame 10, and a part 31 is positioned within this slot. A horizontal rod 28 is attached to frame 10. A spring 32 is attached to the top of rod 28 and to a fixed point on frame 10. A curved lever 33 is connected to the bottom of rod 28. A slot 34 is cut into frame 10, and a part 11 is positioned within this slot. An arrow points to the right, indicating the direction of movement for the various components.

The diagram illustrates a mechanical assembly, likely a cylinder, featuring two main vertical sections. Each section contains a piston rod (e.g., 19, 20) connected to a piston (e.g., 21, 22) and a rod (e.g., 23, 24). A central vertical rod (e.g., 25, 26) is connected to the piston rods. A spring (e.g., 27, 28) is positioned around the central rod. The assembly is labeled with various numbers: 19, 20, 21, 22, 23, 24, 25, 26, 27, 28, 29, 30, 31, 32, 9, 9', 20, 19, 22, 21, 23, 24, 29, 31, and 27. The label '28' is located at the bottom center, and '29' is located at the bottom right.

UNITED STATES PATENT OFFICE

MAX H. KLIEFOTH, OF MADISON, WISCONSIN, ASSIGNOR TO C. F. BURGESS LABORATORIES, INC., OF MADISON, WISCONSIN, A CORPORATION OF DELAWARE

METHOD OF AND APPARATUS FOR MAKING MULTIPLY PAPER

Application filed August 16, 1930. Serial No. 475,697.

My invention relates to the manufacture of fibrous sheets made by laying down a succession of overlapping folds of moist pulp web as disclosed in Patents Nos. 1,737,282 and 5 1,737,283 to Howard F. Weiss and Patent No. 1,737,285 to Max H. Kliefoth, all issued November 26, 1929. The present invention consists of an improvement in the machine and method disclosed in the above mentioned 10 patents.

It is the general object of the invention to provide a fibrous sheet of the character described having greater uniformity of density and greater regularity of side edges where- 15 by trimming wastage is reduced.

It is the specific object of this invention to provide a method and means for smoothing and flattening the looped edges of the folds of moist pulp web before they are conducted 20 to the pressing and drying apparatus.

It is a further object of the invention to provide for the smoothing of the fold edges without the introduction of any additional separate operations upon the web.

25 Other objects and advantages will become apparent from the following description which is to be taken in conjunction with the accompanying drawings wherein:

Fig. 1 is a diagrammatic plan view of the 30 improved apparatus used to make the fibrous sheet;

Fig. 2 is a partial, vertical, sectional view on line 2—2 of Fig. 1;

Fig. 3 is a partial side view, in detail, showing the smoothing device and that portion of the machine at which the moist pulp web is transferred to a moving conveyor, parts being shown in section;

Fig. 4 is a partial end view showing the smoothing device in detail, parts being shown in section;

Fig. 5 is a plan view of a portion of a sheet produced by the machine without the 45 smoothing device;

Fig. 6 is a plan view of a portion of a sheet produced by the machine when equipped with a smoothing device; and

Fig. 7 is a transverse sectional view of a 50 thick sheet which is being built up without

the use of any smoothing and flattening device.

The invention can best be understood by referring to the accompanying drawings in which like numerals indicate like parts in 55 the several figures.

The vat 1 of a wet machine contains the slurry of water and pulp. The usual perforate cylinder mould 2 picks up a web of pulp which is then carried to couch roll 3 around 60 which felt 4 travels in the indicated direction. The wet pulp web is picked up and carried along on felt 4 and is then pressed by press roll 5. The moist pulp web is picked up by press roll 5 and is removed therefrom by doctor 6. The pulp web may be creped by the doctor or may be kept smooth, as desired. The pulp web 8 is then carried forward by conveyor belt 7 which is a part of a hinged reciprocating looping device. The 70 off-take roll 9 (see Fig. 3) of the hinged looping device reciprocates along guide bars 10 and distributes the pulp web 8 transversely upon conveyor 11. It is obvious that the conveyor may also move parallel to the direction of travel of the pulp web, although in the latter case the advantages derived from my invention are not so great.

Tightener roll 12 functions to keep conveyor belt 7 taut and directs the return travel 80 of belt 7 along a path which is at all times as nearly as possible of the same length as the forward path. The pulp web is deposited transversely upon the conveyor 11 in a succession of overlapping folds, adjacent 85 folds being spaced from each other in the direction in which conveyor 11 travels.

To avoid confusion in the use of terms, it is pointed out that throughout the specification and claims the terms "folds" is used to 90 define, not only the folded edge, but the entire overlapping portions formed by each reciprocation of the looping device; and the term "edge" when used in conjunction with "folds" is intended to mean either the folded edge or loop, or the non-folded side edge of the portion of the web forming the folds.

The non-folded side edges of adjacent individual folds are at an angle to each other as illustrated by Figs. 5 and 6. From conveyor 100

11 the succession of overlapping folds usually passes through a continuous press 13, which may be in the form of press rolls. This operation compresses the loosely piled overlapping folds into a coherent sheet. The sheet may continue through the dryer 14 and cutter 15 which cuts the sheet into predetermined lengths.

10 If the laminated board is to be made water-resistant, the water-resistant material may be suspended in the slurry of water and pulp in vat 1 of the wet machine or the water-resistant material may be dusted or sprayed on the pulp web from a suitable device as 8' in Fig. 2.

15 In the formation of a single fold, conveyor belt 7 may be considered as laying down a rectangle of moist pulp web. The movement of conveyor 11, however, distorts the shape 20 of the rectangle into that of a rhomboid. As a result, a twist is given the web at the folded edge with the result that a wrinkled and irregular folded edge is formed, which may or may not fall in line with the edges of the rest 25 of the folds. In the formation of thick fibrous sheets, the movement of conveyor 11 is sufficiently slow to reduce somewhat the twisting effect and the attendant wrinkles and irregularity of edges, but a new difficulty 30 arises. As illustrated in exaggerated fashion in Fig. 7, the loops 35 are more or less rounded causing the material to pile up higher at the edges of the sheet than it does at the intermediate portions. As the relative height of the edge portions increases 35 they become more and more inclined from the horizontal. Since the same length of web is deposited for each successive fold the successive loops approach the mid-portion of 40 the sheet and the folds become shorter if measured horizontally from end to end. The incline of the edge portions finally becomes great enough that the web slumps toward the bottom of the incline as indicated at 36, 45 with the result that the material becomes non-uniformly distributed throughout the width of the sheet. The pressing apparatus to which the sheet is subsequently subjected compresses the material along vertical lines 50 just as it finds it with the result that the compressed sheet is of non-uniform density and its edges are irregular, requiring considerable side trimming.

55 I have found that by the use of a smoothing device, such as that to be hereinafter described, laminated sheets or boards of uniform density may be produced in thicknesses up to one inch and greater.

60 Referring to Figs. 3 and 4, guides 19 are mounted on guide bars 10 and are reciprocated by means of a suitable source of power, such as a cam and cam follower (not shown). Roller 9 is provided with a shaft 9' mounted in journals 20 carried by guides 19 whereby 65 the end of the reciprocating-looping device

is reciprocated with the guides 19. U-shaped brackets 21 are mounted in a fixed position upon reciprocating guides 19 by suitable means, as bolts 22. Z-shaped actuating members or levers 23 are mounted pivotally on brackets 21 by means of pins 24. In similar manner levers 25 are mounted below levers 23 upon brackets 21 by means of pins 26. The lower ends of levers 25 are fastened rigidly to and from a part of frame 27. Rolls 28 and 28a are rotatably mounted at the ends of frame 27. Pins 29 are mounted rigidly upon the lower ends of levers 23 to cooperate with slots 30 in the upper ends of levers 25. Springs 31 are fastened at their respective ends to levers 23 and frame 27 to aid in returning frame 27 into the inoperative position and to prevent its too free and unrestricted motion. Trip-blocks 32 are mounted upon guide bars 10 to cooperate with 80 Z-shaped levers 23 to actuate rolls 28 and 28a into operative positions.

85 To more clearly set forth the operation of the smoothing device a cycle of operation of the apparatus will be described. As shown in Fig. 3, a number of folds of pulp web have been deposited on conveyor 11 and the edges smoothed down as shown most clearly at 33. The looping device has folded the web at 34 and has laid another fold on conveyor 11 during its return motion. The rounded loop is clearly shown at 34 while the previously laid folds have been smoothed down. In the position shown, the looping mechanism with the attached smoothing device is in a position 90 to begin its forward motion to the left as shown by the arrow. With the starting of such forward movement an additional loop is formed at 33 and an additional fold is started across conveyor 11.

95 As the looping device reaches the central point at its forward travel, Z-shaped levers 23 engage trip-blocks 32. Further forward movement of reciprocating guides 19 causes levers 23 to rotate in a clockwise direction 100 about pins 24. Cooperation between pins 29 on levers 23 and slots 30 in levers 25 cause the latter, together with the attached frame 27, to rotate in a counter-clockwise direction about pins 26. The tilting of frame 27 with the attached rolls 28 and 28a causes roll 28 to contact with fold 34 and upon further forward movement of the reciprocating looping device, roll 28 smooths the folded edge 105 at 34 and reduces the rounded edge to a flat edge. Further forward movement of guides 110 19 causes levers 23 to pass beyond trip-blocks 32 and allow frame 27 to return to the horizontal or inoperative position and levers 23 and 25 to their vertical position as shown in 115 Fig. 3.

120 As the looping device reaches the forward point of its travel and begins its return movement another loop is formed at 34 and another fold is started across conveyor 11.

As the looping device reaches the central point of its travel, levers 23 again engage trip-blocks 32. Further travel of the looping device causes levers 23 to rotate in a counter-clockwise direction about pins 24. Cooperation between pins 29 on levers 23 and slots 30 in levers 25 causes the latter, together with attached frame 27, to rotate in a clockwise direction about pins 26. The tilting of frame 27 with attached rolls 28 and 28a causes roll 28a to contact with the pulp web and on further movement of the looping device, roll 28a smooths down the folded edge at 33. Further movement of guides 19 cause levers 23 to pass beyond trip-blocks 32 and allow frame 27 to return to its inoperative position as heretofore described. The looping device continues to its rear-most position and the cycle of operation is repeated.

Since rolls 28 and 28a are moving outwardly with respect to the fibrous sheet during their contact therewith they exert outward components of force as well as vertically downward components with the result that the material at the looped portions of each fold is flattened and drawn out evenly to the edge and there is no local accumulation of material and all of the looped edges are substantially in line.

If desired the smoothing rolls may be actuated so as to smooth the entire fold. In this case smoothing roll 28 would be actuated so as to begin its contact with the fold at the center of the fold during the forward travel of the off-take roll. Smoothing roll 28a would likewise begin its contact with the fold at the center of the fold during the return travel of the off-take roll.

The drawings and description of the smoothing mechanism are specific for the purpose of illustration, but it is evident to a person skilled in the art that the details may be altered without departing from the spirit of the invention.

I claim:

1. In a machine of the class described, a reciprocating looping device for laying down a succession of overlapping folds of moist pulp web, reciprocating guides for said looping device, stationary guide supports for said guides, an edge-smoothing device for said folds, said edge-smoothing device comprising in combination, brackets depending from said guides, a frame supported pivotally upon said brackets, smoothing rolls mounted in the respective ends of said frame, actuating levers pivotally mounted upon said brackets, trip-blocks mounted upon said guide supports, said levers and said trip-blocks being adapted to cooperate with each other and with said frame to move a smoothing roll into contact with opposite looped edge portions of said folds with each successive reciprocating movement of said looping device, and coil springs fastened between said

actuating levers and the end portions of said frame to move said smoothing rolls into the inoperative position, said smoothing contact being made while said roll is moving outwardly with respect to the fold.

2. In a machine of the class described, in combination, a reciprocating off-take roll, reciprocating guides for said off-take roll, a bracket depending from each of said guides, a frame pivotally supported between said brackets, a cylindrical roll rotatably supported at each end of said frame, a lever pivotally mounted upon each of said brackets in engagement at one end with said frame, horizontal guide bars for said guides, trip-blocks mounted upon said guide bars adapted to engage said levers at their opposite ends during reciprocation of said off-take roll, and springs attached between the lower ends of said levers and portions of said frame intermediate its points of support and its ends.

3. In a machine of the class described, in combination with a reciprocating off-take roll, reciprocating guides for said off-take roll, guide supports for said guides, a frame pivotally suspended from said guides, cylindrical rolls rotatably mounted transversely upon the respective ends of said frame, and means comprising trip-blocks upon said guide supports cooperating with means comprising levers supported by said guides to impart predetermined pivotal motion to said frame with each reciprocating movement of said off-take roll.

4. In a machine of the class described, in combination with a reciprocating off-take roll for laying down a succession of overlapping folds of moist pulp web and a support for guiding and imparting reciprocating motion to said off-take roll, a device for smoothing and flattening the looped edges of said folds, said device comprising brackets mounted upon said support and reciprocating therewith, a frame pivotally suspended from said brackets, smoothing rolls mounted upon said frame, and means for moving said smoothing rolls into contact with opposite looped edge portions of said folds on each successive reciprocating movement of said off-take roll.

5. In a machine of the character described, in combination with a moving conveyor and a reciprocating looping device for laying down a succession of overlapping folds of moist pulp web upon said conveyor, a device for smoothing and flattening the looped edges of said folds, said device comprising rolls mounted upon said looping device and adapted to be lowered into contact with said folds, and means for lowering one of said rolls into contact with opposite looped edge portions of said folds on each successive reciprocating movement of said looping device.

6. A machine for making fibrous sheets comprising in combination, means for forming moist pulp web, means for laying

- down said moist pulp web in a continuous succession of overlapping folds, means for smoothing and flattening individually the looped edge-portions of said folds, means for regularly spacing said individual folds 5 in the machine direction of the finished sheet, means for pressing said folds into a coherent sheet, means for drying said compressed sheet, means for side-trimming the edges of said dried sheet, and means for cutting said sheet into lengths. 75
- 10 7. A machine for making fibrous sheets comprising, in combination, means for forming a moist pulp web, means for treating said web with foreign substances, means for laying down said moist web in a continuous succession of overlapping folds, means for smoothing the looped edges of said folds, means for regularly spacing said individual 15 folds in the machine direction of the finished sheet, means for compressing said folds of moist web into a coherent sheet, means for drying said compressed sheet and means for cutting said sheet into lengths. 80
- 20 8. In a machine for making a water-resistant sheet, the combination of means for treating a moist pulp web with a water-resistant material, means for laying down said treated web in a continuous series of overlapping 25 folds, means for smoothing and flattening the looped edges of said folds and means for pressing and drying said folds to form a dry, coherent, water-resistant, fibrous sheet. 85
- 30 9. In a machine of the character described, 35 in combination with a moving conveyor and a reciprocating looping device for laying down a succession of overlapping folds of moist pulp web upon said conveyor, of means for smoothing and flattening individually 40 the looped edges of said folds. 90
- 35 10. In a machine for making thick fibrous sheets, the combination of means for laying down a series of overlapping folds of moist pulp web on a conveyor and means for 45 smoothing and flattening the looped edges of said folds. 95
- 40 11. In a machine of the character described, means for smoothing and flattening the looped edges of the overlapping folds of moist 50 pulp web as said folds are laid on a moving conveyor. 100
- 45 12. The method of making a fibrous sheet which comprises laying down a continuous series of overlapping folds of moist pulp web, 55 smoothing and flattening the looped edges of said folds and pressing said moist webs into a coherent sheet. 105
- 50 13. The method of making a fibrous sheet which comprises laying down a moist pulp 60 web transversely upon a moving conveyor to form overlapping folds of moist pulp web, smoothing and flattening the looped edges of said folds and pressing said overlapping folds into a coherent sheet. 110
- 55 14. The step in the method of making a 65 fibrous sheet by laying down a plurality of overlapping folds of moist pulp web on a moving conveyor which comprises smoothing and flattening the looped edges of said folds as each successive fold is laid on said conveyor. 115
